US0D1080152S

(12) United States Design Patent (10) Patent No.: US D1,080,152 S
(45) Date of Patent: * Jun. 24, 2025

(54) FOOTWEAR

(71) Applicant: Crocs, Inc., Broomfield, CO (US)

(72) Inventor: Alexander Jacob Mayhew, Denver, CO (US)

(73) Assignee: Crocs, Inc., Broomfield, CO (US)

() Term: 15 Years

(21) Appl. No.: 29/891,472

(22) Filed: May 5, 2023

(51) LOC (15) Cl. 02-04

(52) U.S. Cl.

USPC D2/916

(58) Field of Classification Search

USPC D2/896, 900, 916, 917, 918, 919, 920, D2/921, 922, 923, 924, 925, 926, 927, D2/969, 971

CPC A43B 3/10; A43B 3/12; A43B 3/14; A43B 3/26; A43B 3/101; A43B 3/102; A43B 3/103; A43B 3/105; A43B 3/106; A43B 3/122; A43B 3/124; A43B 3/126; A43B 3/128; A43B 1/10; A43B 5/08

(57) CLAIM

The ornamental design for a footwear as shown and described.

DESCRIPTION

FIG. 1 is a front perspective view of a footwear;

FIG. 2 is a front view thereof;

FIG. 3 is a back view thereof;

FIG. 4 is an outer side view thereof;

FIG. 5 is an inner side view thereof;

FIG. 6 is a top view thereof; and,

FIG. 7 is a bottom view thereof.

The elements shown in FIGS. 1-7 that are overlaid with a white transparent mask bounded by broken lines represent portions that form no part of the claimed design.

1 Claim, 7 Drawing Sheets
